(57) **CLAIM**

What is claimed is the ornamental design for a hockey stick handle/grip, as shown and described herein.

DESCRIPTION

FIG. 1 is a perspective view of the invention with a portion shown in phantom lines for environmental purposes only; FIG. 2 is a front elevational view thereof; FIG. 3 is a left side elevational view thereof; FIG. 4 is a right side elevational view thereof; FIG. 5 is a top plan view thereof; and, FIG. 6 is a bottom plan view thereof. The rear of the invention is a mirror image of the front. The broken line showing is for illustrative purposes only and forms no part of the claimed design.
